TILT TABLE CONTAINER WITH MEASURING TRAP

Louis D. Friedman, New York, N. Y.

Application March 21, 1946, Serial No. 656,103

6 Claims. (Cl. 222—455)

1

This invention relates to bottle closures, and more specifically, to a bottle attachment for dispensing a measured quantity of liquid.

An object of the invention is to provide a removable attachment for use as a bottle closure, said attachment being adapted to dispense a predetermined quantity of liquid from the bottle.

Another object is to provide a bottle attachment so designed that the mere tilting of the bottle in the usual decanting manner will dispense a measured quantity of liquid therefrom.

A further object is to provide an attachment adapted to be used as a closure for bottles having mouths and necks of different sizes.

Still another object is to provide an attachment with detachable auxiliary elements to vary the quantity of liquid to be dispensed in a single dose.

These and other objects are accomplished in part by providing an attachment of the class specified comprised of a removable stopper element, a central tube, two containers or measures, two feed tubes and two discharge tubes. The attachment can be provided with a plurality of stopper elements having the same sized bore but differing in the size of the over-all diameter, so that they can effectively seal the mouths of different sized bottles. The central tube is open at one end and closed at the other, the open end being capable of fitting snugly in the bore of the stopper element.

The containers are opposingly disposed about the central tube, each being connected to it by one of the feed tubes. Each discharge tube joins one of the containers at a junction below the feed tube, and extends outwardly and upwardly from the container, the nozzle of the discharge tube being above the container to prevent discharge of liquid therefrom prior to tilting for decanting purposes.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a front view of a bottle attachment for dispensing a measured quantity of liquid, said attachment embodying features of the invention herein.

Fig. 2 is a side view of the attachment shown in Fig. 1.

Fig. 3 is a top view of the attachment.

2

Fig. 4 is a sectional view through the line 4—4 of Fig. 1.

Fig. 5 is a sectional view through the line 5—5 of Fig. 3.

Fig. 6 is a front view of the bottle attachment canted as in dispensing liquid therefrom.

Fig. 7 is a front view of a modified bottle attachment for dispensing a measured quantity of liquid.

Fig. 8 is a sectional view through the line 8—8 of Fig. 7.

In the drawings and in the specification, in which like reference numbers designate similar elements, the numeral 10 designates a bottle attachment for dispensing a measured quantity of liquid, said attachment being shown in Figs. 1 to 6 inclusive and embodying features of the invention herein.

The attachment 10 is provided with a removable stopper 11 in the form of a cylindrical tube having a bore 12. In order to adapt the attachment to fit bottles with necks of different dimensions, stoppers 11, each having the same sized bore 12 but varying in their over-all diameters, can be furnished with the device. A central tube 13 with a transverse shoulder 14 intermediate its ends is positioned with its lower portion 15 fitting tightly in the stopper bore 12, and its shoulder 14 resting on the top of the stopper and extending beyond it. In functioning position attached to a bottle (see Fig. 1), the protruding portion of the shoulder rests about the mouth of the bottle, and an upper portion 16 of the central tube rises above and out of the bottle, the stopper and shoulder effectively sealing the bottle against escape of liquid at the line of attachment. An air vent 17, extending through the wall of the upper portion 16 of the central tube, facilitates the free movement of liquid from the bottle by preventing the formation of a vacuum therein.

Two diametrically opposite feed tubes 18 extend outwardly from the central tube upper portion 16 at its closed top 19, each of said feed tubes joining and entering a measure or container 19 of predetermined liquid capacity. The containers, which are opposingly disposed about the central tube, are cylindrical in form with curved walls 20 and flat sides 21.

Each feed tube is positioned partly within and partly outside one of the containers, entering it at the top of its curved wall 20, the inside portion 22 of the feed tube extending around a part of the curved top of the container. Each container is provided with a discharge tube 23 which extends outwardly and upwardly from the curved

wall 20 below the feed tube, each discharge tube reaching in the direction of the opposite container, the axis of the discharge tube being approximately parallel to the flat walls of the opposite container. The terminus or spout 24 of each discharge tube 23 is above the topmost points of the containers so that liquid in the container will not be discharged through the discharge tube 23 until the attachment is tilted for decanting.

The attachment 10 functions as follows:

The bottle with the attachment fitted thereto as hereinabove described is first tilted so that one of the containers 19 is at a lower level than the mouth of the bottle (see Fig. 6) so that liquid will flow from the bottle through the central tube 13, down one of the feed tubes 17 and into the lower container, filling it. The bottle is then tilted so that the filled container is uppermost and the empty container in lower position. Liquid from the uppermost filled container will now flow through its discharge tube 23 and out of the spout 24, the inside portion 22 of the feed tube acting as a trap to prevent the liquid from re-entering the bottle, simultaneously liquid from the bottle will flow therefrom down into the central tube 13 and down the lower feed tube 17 filling the lowered container. Thus one of the containers can always be filled while the other is being discharged, the amount of discharge being predetermined and equal to the capacity of the container. The attachment can be removed and the filled container discharged without filling its mate when desired.

Figures 7 and 8 show a modified bottle attachment 25 for dispensing a measured quantity of liquid. The attachment 25 is provided with two modified containers or measures 26 each of which has an opening 27 in its base from which a short threaded neck 28 extends.

Two supplementary containers 29, each with an opening 30 and a threaded neck 31 capable of engaging the neck 28, can be removably secured to the measures 26 to increase the capacity of a discharge or loading. When the supplementary containers are not used, a threaded cap (not shown) can be screwed on the container neck 28 to seal its base opening 27.

In all other respects, the attachment 25 is in every way similar to the attachment 10 heretofore described and is operated in the same manner.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. For use with a bottle, a removable attachment for dispensing a measured quantity of liquid therefrom, said attachment comprising a central tube, two feed tubes, two measures and two discharge tubes, the central tube having an open end adapted to connect with the bottle, each feed tube extending outwardly from the other end of the central tube connecting it with one of the measures and having a portion extending about the inside of the measure at its top, the measures being opposingly disposed about the central tube, and each discharge tube extending outwardly and upwardly from one of the meas-

ures, each of said discharge tubes terminating in an open end positioned above the topmost portion of the inner walls of the other measure.

2. For use with a bottle, a removable attachment for dispensing a measured quantity of liquid therefrom, said attachment comprising a central tube, two feed tubes, two measures and two discharge tubes, the central tube having an open end adapted to connect with the bottle, each feed tube extending outwardly from the other end of the central tube connecting it with one of the measures and having a portion extending about the inside of the measure at its top, the measures being opposingly disposed about the central tube, and each discharge tube extending outwardly and upwardly from one of the measures, each of said discharge tubes terminating in an open end positioned above the topmost portion of the inner walls of the other measure, the junction of each measure with its discharge tube being below the junction with its feed tube.

3. For use with a bottle, a removable attachment for dispensing a measured quantity of liquid therefrom, said attachment comprising a stopper element, a central tube, two feed tubes, two containers and two discharge tubes, the stopper element having an opening therethrough, the central tube having an open end adapted to fit snugly within the stopper opening, each feed tube extending outwardly from the other end of the central tube connecting it with one of the containers and having a portion extending along the inside of the container near its top, the containers being opposingly disposed about the central tube, and each discharge tube extending outwardly and upwardly from one of the containers.

4. For use with a bottle, a removable attachment for dispensing a measured quantity of liquid therefrom, said attachment comprising a stopper element, a central tube, two feed tubes, two containers and two discharge tubes, the stopper element having an opening therethrough, the central tube having an open end adapted to fit snugly within the stopper opening, and a shoulder extending transversely thereabout intermediate its ends, each feed tube extending outwardly from the other end of the central tube connecting it with one of the containers and having a portion extending along the inside of the container near its top, the containers being opposingly disposed about the central tube, and each discharge tube extending outwardly and upwardly from one of the containers, each of said discharge tubes terminating in an open end positioned above the topmost portion of the inner walls of the other container, the junction of each container with its discharge tube being below the junction with its feed tube.

5. For use with a bottle, a removable attachment for dispensing a measured quantity of liquid therefrom, said attachment comprising a stopper element, a central tube, two feed tubes, two containers, two auxiliary containers and two discharge tubes, the stopper element having an opening therethrough, the central tube having an open end adapted to fit snugly within the stopper openings, each feed tube extending outwardly from the other end of the central tube connecting it with one of the containers and having a portion extending along the inside of the container near its top, the containers being opposingly disposed about the central tube, each auxiliary container being removably secured to one of the containers increasing its capacity, and each

discharge tube extending outwardly and upwardly from one of the containers.

6. A pouring spout for bottles, comprising a central tube which may be coupled to the neck of a bottle and feed tubes extending in opposite direction from and communicating at their inner ends with said central tube, a measuring container enclosing the outer end of each feed tube, and a discharge tube extending from each container outwardly of both containers, the discharge tubes being disposed in intersecting relation to each other, whereby a measured quantity of fluid may be discharged from a bottle from one of the containers and the other container will permit air to enter the bottle through its feed tube and the 15 central tube.
